UNITED STATES PATENT OFFICE.

FRANKLIN W. OEHRL, OF PHILADELPHIA, PENNSYLVANIA, ASSIGNOR TO OEHRL BROTHERS COMPANY, OF PHILADELPHIA, PENNSYLVANIA, A CORPORATION OF PENNSYLVANIA.

MACHINE FOR MAKING ORNAMENTAL ROPE OR CORD.

1,273,912.

Specification of Letters Patent. Patented July 30, 1918.

Application filed July 1, 1911, Serial No. 636,401. Renewed December 14, 1917. Serial No. 207,201.

To all whom it may concern:

Be it known that I, FRANKLIN W. OEHRL, a citizen of the United States, and a resident of Philadelphia, county of Philadelphia, State of Pennsylvania, have invented certain new and useful Improvements in Machines for Making Ornamental Rope or Cord, of which the following is a specification.

10 My invention relates to improvements in machines for making ornamental ropes and cords, in which the strands of threads of yarn of the same or different colors and of any desired and suitable material are brought together and wound around a former of any convenient shape and simultaneously around one of two binding threads, the other binding thread being brought into position outside of the coils 15 or loops formed around said former. The binding threads are twisted together in a known manner to bind one wall of said loops between the said threads. The loops project laterally from the said binding 20 threads and the body of loops extend around the said threads, the latter being in effect a core, in the form of a continuous spiral.

One object of my invention is to provide means for conveniently bringing the strands 30 of thread forming the loops together and winding them around a stationary former.

Another object of my invention is to provide an improved means for winding loop threads around one of the binding threads.

35 A further object of my invention is to provide means for maintaining the former in stationary position.

A still further object of my invention is to provide means whereby instead of allowing the looped threads to extend uncut and spirally around the twisted binding threads, the spirally arranged loop threads or strands may be cut to thereby form what is known in the trade as plush ropes or 45 cords.

The underlying purpose of my invention is to provide a machine which is simple in construction and which is at the same time efficient and rapid in operation.

50 Other objects and advantages than those above pointed out will be referred to specifically hereinafter in the specification or else will be apparent therefrom.

In order that my invention may be more

readily understood and comprehended, reference should be had to the accompanying drawings in which convenient forms of embodiment of the same are illustrated but it should be understood that changes in the details of construction within the scope of the claims may be made without departing from the spirit of my invention.

In the drawings:

Figure 1 is a top plan view of a portion of a machine embodying my invention; 65

Fig. 2 is a view partly in side elevation and partly in vertical longitudinal section;

Fig. 3 is an enlarged sectional view of a portion of the machine showing details of construction; 70

Figs. 4, 5, 6 and 7 are transverse sections taken along the line 4—4 of Fig. 1 and showing the parts illustrated in said figures in different positions;

Fig. 8 is a top plan view with certain portions in section of an attachment for cutting the loop strands or threads of the ornamental rope or cord; 75

Fig. 9 is a vertical longitudinal sectional view of the same with certain portions in side elevation;

Fig. 10 is a view taken on the line 10—10 of Fig. 8;

Fig. 11 is a transverse sectional view taken on the line 11—11 of Fig. 8; and 85

Fig. 12 is a view of a modified construction of tube for guiding loop threads in groups of different colors.

In the drawings illustrative of my invention, I have omitted therefrom all parts and portions of machinery and mechanism which are not essential to my invention. For instance, I have not shown the power devices by means of which certain parts of the machine embodying my invention are revolved, 95 nor have I shown the spools (or the rack with the spindles for supporting the same) from which the strands of thread of textile or other material are taken of which the loops of the ornamental rope or cord are 100 formed.

Certain other mechanism which has been omitted will be pointed out as the detailed description of my invention progresses.

Referring to Figs. 1 to 7 of the drawings: 105

1 designates the base member of the frame upon which the operative parts of my invention are supported, and 2 and 3 designate

upright members secured to the said base member, such upright members constituting the immediate support for the operating parts of my invention.

5 4 designates a revoluble hollow member mounted in bearings in the upright members 3 which is driven by means of a gear wheel 5 secured thereto by means of a set screw 6. The means for driving the gear 5
10 are not shown.

For simplicity of construction the member 4 should be tubular but it may be of any other shape desired.

15 The revoluble member 4 is provided with bearing plugs or blocks 9 and 10 in which a thread guide member 11 is loosely mounted and is held against longitudinal movement therein in one direction by means of a collar 12 in contact with the inner end of the 20 plug or block 10, and against longitudinal movement in the opposite direction by means of a gear 13 situated against the outer side of the plug or block 10.

25 The purpose and object of the gear 13 will be hereinafter referred to and described.

30 The end of the thread guide 11 projects beyond the gear 13 and is provided with a former 14 which is secured thereto in the manner indicated in Fig. 3 in which the said former is shown as being provided with a tube-like projection 15 which projects into the tubular end of the guide member 11.

35 The former 14 preferably is detachable, as illustrated, in order that formers of different sizes may be used from time to time as desired so as to form loops of different diameter.

40 A collar 16 is provided which surrounds the end of the tubular member 11 and rests against the rear end of the former 14 and the parts secured and connected together by means of a binding screw 17.

45 The tube 11 serves as a guide for a thread 20 which constitutes the inner binding thread of the rope or core. The outer binding thread is shown at 21 as being led from a spool 22 mounted on the brackets 23 supported upon the base 1 of the frame of the machine. The outer binding thread 21 extends over a roller or sheave 24, as illustrated.

50 It should be noted here that the binding thread may consist either of a textile material, metallic wires, or any other suitable material.

55 The inner binding thread 20 is taken from a revoluble spool 25 co-axial with the revoluble hollow member 4. Preferably the said spool is fast upon a tubular sleeve 26 which 60 in turn is supported upon the tubular member 27, the spools being thereby protected against unnecessary wear.

65 The tubular member 27 is held in position in the upper end of the upright 2 by means of the binding screw 28.

The spool is prevented from overrunning itself and its revolution is controlled by means of a brake cord or band 29 connected at one end to the frame of the machine and extending thence over the flange 30 of the 70 spool, resting in a groove 31 therein, and its opposite end being provided with a weight 32.

75 The thread from the spool 25 is passed through loop guides 33 upon one member 34 of what may be termed a flier upon the revoluble member 4, the thread passing from the said loop guides to the guide 11, as is indicated best in Fig. 2. The other member 35 of the flier is provided for the purpose 80 of maintaining the revoluble member 4 in proper balance.

85 The thread upon the spool 25 is so wound that in being unwound therefrom the spool is rotated in the same direction as the revoluble member 4. By reason, therefore, of the connection of one member of the flier with the thread drawn from the spool 25 the latter is caused to revolve with the revoluble member 4 and in addition thereto is 90 given an additional speed of revolution due to the drawing off of the binding thread 20 by the twister (not shown).

95 The ornamental loops, strands or threads 36 may consist of any suitable number and are taken from spools supported upon a rack, the said rack and spools not being illustrated. The said strands or threads may consist of any suitable material such as silk, cotton, wool or other fabric, and 100 may be of the same or different colors. The threads are conducted and directed to a position in proximity to the former 14 by means of the tubular guiding member 37. The forward end of the said guiding member terminates at a point laterally of the 105 larger end of the said former 14.

110 Except for the fact that said spools revolve upon their spindles or other supports to permit the unwinding of the threads or strands thereupon they are stationary so that when the thread is exhausted from a spool such spool may be replaced by another without stopping the operation of the machine.

115 It should be stated, perhaps, here that the former 14 is, generally speaking, of what may be described as truncated cone shape, as is indicated in the drawings.

120 The rear end of the tubular guiding member 37 is supported by means of a universal joint connection at the upper end of a support designated as a whole by the reference numeral 38. The said support 38 consists of a sleeve like member 39 which constitutes 125 a bearing for the pivotal member 40. The member 40 is secured in place by means of the key 41. The said member 40 and the sleeve 39 occupy vertical positions.

130 The upper end of the member 40 is bifur-

cated and in the bifurcations the supporting block or member 42 is pivoted. In or to the latter the rear end of a tubular guiding member 37 is rigidly secured and held 5 against rotation about its own axis.

The point of inter-section of the axes of the pivoted member 42 and of the upright pivoted member 40 is co-axial with the revoluble member 4.

10 The tubular guiding member 37 extends from its point of connection to the pivoted members 42 and 40 through the tubular member 27 and through the tubular revoluble member 4 and is inclined to the axis of 15 the member 4 as is clearly shown. The said member 37 extends through openings 43 and 44 in the plugs or blocks 9 and 10. As already stated the member 37 is held against 20 rotation on its own axis but it is obvious that it has a movement of revolution with the revoluble member 4 being carried around the axis thereof and outlining in its movements the figure of a cone having its apex at the point of connection of the said guiding 25 tube 37 with the members 42 and 40 and its base being formed by the line or lines of revolution formed by the forward end of the said tubular guiding member 37.

45 designates a gear or pinion member 30 secured to the member 37 at a point adjacent to or in contact with the outer or forward end of the plug 10. The said gear or pinion member 45 is in engagement with the intermediate gear 46 and the latter is 35 in engagement with the gear 13 to which reference has already been made. The gear 46 is revolvably mounted upon a journal or pivot 47 secured to the plug or block 10.

As already stated the guiding member 37 40 is held securely against rotation about its own axis. The gear 45 is firmly secured to the said member 37 so that it is also held against rotation.

The gears 45 and 46 are bodily revolved 45 about the axis of the revoluble member 4.

Upon reference to Figs. 4, 5, 6 and 7 it will be observed that the position of the gear 45 changes with respect to the position of the gear 46; that is to say, in the position 50 illustrated in Fig. 4, the gear 46 is to the right of and is below the gear 45; after being moved to the position indicated in Fig. 5 the gear is still to the right of but is located above the gear 45; thereafter movement of the parts to the position indicated 55 in Fig. 6 brings the gear 46 to the left of the gear 45, said gear 46 still, however, remaining above the gear 45; and after a further movement to the position indicated 60 in Fig. 7, with the gear 45 in horizontal alignment with the gear 13, the gear 46 is below and somewhat to the left of the gear 45.

It will be understood that as the gears 65 45 and 46 are revolved with the revoluble

member 4 they assume an infinitude of other relations to each other at positions intermediate the specific positions referred to and which are illustrated.

When the revoluble member 4 is revolved 70 in the direction indicated by the arrow in Fig. 4 and in view of the fact that the gear 45 and the guiding member 37 are firmly held against rotation about their axes, rotation of the gear 46 about its axis in a direction opposite to that in which the hands of a watch move is effected. If, however, the member 4 were revolved in the opposite direction the gear 46 would also be rotated in the opposite direction, that is, in the direction of the movement of the hands of a watch or clock.

The purpose of providing the intermediate gear 46 which is in engagement with the gears 45 and 13, is to prevent revolution 85 of the latter with the revoluble member 4 upon which it is supported and thereby hold or maintain the former in stationary position.

In the construction illustrated in which 90 the former 14 (about which the loop threads or strands which pass through the guide member 37 from the spools at the opposite end of the machine are wound) is supported upon the inner thread guiding member 11 95 it is necessary that the former shall be held in stationary position. If on the contrary the former and the member 11 rotated or revolved with the revoluble member 4 it is plain to be seen that the loop threads or strands 36 issuing from the guide member 37 would not be wound around the said former.

The forward ends of the binding threads 20 and 21 are connected to a twister (not 105 shown) of known construction and which travels or moves away from the former 14 in a known manner, with the result that the inner and outer binding threads 20 and 21 are twisted together as is indicated at 49 in 110 Fig. 2.

It will be observed that the outer binding thread 21 passes over the roller or sheave 24 as already stated and into position adjacent to the threads or strands which are 115 wound around the former 14.

By reason of the fact that the former 14 is of the same general shape as that of a truncated cone, the winding of the strands of thread thereabout, as indicated in Fig. 2 120 of the drawings, tends to push the previously wound threads therefrom and such tendency in connection with the fact that the binding threads 20 and 21 are drawn forward by the twisting device, are important factors in 125 causing the threads or strands which are wound about the said former to slide therefrom.

The roller 24, however, actually controls 130 the feeding of the looped or coiled threads

from the said former 14. The said roller being in contact with the threads coiled upon said former feeds the same therefrom, but at the same time prevents the same from sliding therefrom too rapidly.

The walls of the spiral threads at one side of the coil are held between the inner and the outer binding threads and as the latter are twisted and held firmly together 10 the body of the loops of thread projects laterally from the twisted threads 49 which constitute in effect a core of the rope or cord and extend along the same in the form of a continuous spiral.

15 The outer binding thread, may, as is usual, be provided with a coating of cement or adhesive of some kind.

In the manufacture of plush rope or cord it is necessary that the spiral loops heretofore described shall be cut.

20 In Figs. 8 to 11 I have illustrated one form of construction which is suitable for that purpose.

In said figures, 50 designates a bracket 25 which rises from any suitable part of the frame of the machine, which bracket is provided with a laterally projecting part 51 which serves as a support for the tubular former 52.

30 Unlike the construction illustrated in Figs. 1, 2 and 3 the former in this construction is supported independently of the central guide 11. The former 52 is provided with a slot 53 into which projects a cutting member 54 which, in the construction illustrated, is circular in order that the same may be adjusted from time to time so as to bring a different portion thereof readily into cutting position.

35 The cutting member 54 is supported upon a pivot 56 which in turn is supported upon a depending adjustable bracket 57. The cutting member 54 may be adjusted by loosening the wing nut 58. It may be noted that 45 the cutting member is held between a washer 59 and a ring or sleeve 60 both of which are seated upon the pivot 56. The purpose of making the bracket 57 adjustable is that the knife may be moved firmly against the wall 50 at the end of the slot 53 for the purpose of preventing the ornamental strands or threads from passing between the edge of the cutting member 54 and the end wall of the slot.

55 The enlarged end of the former 52 is provided with notches or indentures 61 and 62 for a purpose to be hereinafter set forth.

60 63 designates a member secured by means of a binding screw 64 to the forward end of the guiding member 11. The greater portion of the forward part of the said member is removed as is indicated in Figs. 8 and 9 of the drawings, for the purpose of providing a convenient support for guide rolls 65.

65 In order to hold the member 63 in pre-de-

termined relation to the rear end of the former 52, I have provided the rod 66, the forward end of which is in contact with the upper portion of the rear end of the said former 52. For a reason to be hereinafter 70 more specifically referred to, considerable pulling force is exerted upon the rollers 65 and consequently upon the member 63 and it is the purpose of the rod 66 to cause such pulling force to be resisted by the former 52 75 instead of permitting it to be applied to the member 11 and increase the friction between certain parts carried thereby and certain parts carried by the revoluble member 4.

In Fig. 8 I have shown the forward end 80 only of the guide member 37 by means of which the loop strands or threads 36 are wound around the former 52.

The binding thread 20, as illustrated, 85 passes through the guide member 11, between the forward end of the member 63 and the rear end of the former 52, and thence through the notch 62, and along the under side of the former 52, while the outside binding thread 21 passes upwardly and 90 over the roller or sheave 24 in the same manner, as is illustrated in Figs. 1 and 2.

The forward ends of the said binding threads 20 and 21 are attached to a twister (not shown) which moves forward and 95 away from the said former and at the same time twists the said binding members together so as to bind the loop threads or strands there between.

The roller 24 tends to feed the loop 100 threads forward but in order that the said loop threads may be fed and drawn more positively against the cutting member 54, I have provided an endless cord 70 of any suitable material, preferably textile (though 105 wires may be used for that purpose), which preferably should be of considerable length and which is passed through the hole or perforation through the former 52 as indicated most clearly in Fig. 8 of the drawings, and extends around the rollers 65 and thence through the notches 61 as illustrated and along the sides of the straight portion of the former 52. The loop strands or threads are wound or coiled around the former and 115 at the same time around the portions of the threads or cords 70 around the opposite sides of the said former.

By driving means (not shown) the thread or cord 70 is caused to travel in the direction indicated by the arrows in Fig. 8 whereby the portions of the said cord upon opposite sides of the former 52 and around which the loop strands 36 are wound draw the said strands against the edge of the cutting member 54 so that the said loop strands are cut with the result that the cut ends of the loop strands project laterally from the twisted binding threads and extend around the same in the form of a continuous spiral.

It should be understood that the member 11 and the member 63 secured thereto are held in stationary position by some means such as is illustrated for that purpose in 5 Figs. 1 to 7 inclusive.

In the employment of my invention the inner binding thread is taken or unwound from the spool 25 in untwisted condition and the same is twisted between the said spool 10 and the forward end of the former 14 or rear end portion of the former 52.

As already noted, the thread 20 is so wound upon the spool 25 that when unwinding the same therefrom the spool is rotated 15 in the same direction as the revolution of the revoluble member 4 and consequently in the same direction as the member 37. By this arrangement I have provided means which prevents the twisting of the inner 20 binding thread 20 around the guide member 37 notwithstanding the fact that the latter is revolved around the central guide member 11 for the inner binding thread 20.

In Fig. 12 I have shown a construction of 25 guiding tube for the loop threads which is well adapted for use when it is desired to employ loop threads of different colors. When threads of different colors are employed it is preferable that they should be 30 wound upon the former in different groups. The effect is more ornamental.

In the tube 37 I have provided a cross wire 71 in the forward end and one group 35 of threads 72 of one color (say red) issue from the said tube upon one side of the cross wire and another group 73 of another color (say green) from the opposite side. The group of red threads enter the tube through a notch 74 near its rear end; while the other 40 group of green threads enter the rear end of said tube as indicated. At the notch I provide a dividing member 75 over which the group of threads 72 pass and under which the other group 73 pass. By the employment 45 of the dividing plate or member 75 the threads of the two groups are prevented from becoming entangled.

Having thus explained the nature of my 50 said invention and described some of the ways of making and using the same although without attempting to set forth all of the forms in which it may be made or all the modes of its use, what I claim is:—

1. In a machine of the character described, the combination of a revoluble support, a former, means whereby said former is loosely supported by said support, and a thread or strand guiding means a portion of 55 which revolves around said former.

2. In a machine of the character described, the combination of a revoluble support, a former having connection with said support, a thread or strand guiding member supported upon said support, a portion of 60 which member revolves around said former

to wind or coil the said threads or strands thereon, means for holding the said thread or strand guiding member against revolution on its own axis, and means for permitting a change of position of said support with respect to said member. 70

3. In a machine for making ornamental rope or cord, means for supporting and supplying to the proper points inner and outer binding threads, means for supporting and guiding the loop threads or strands of the rope or cord, means for causing revolution of the said supporting and guiding means, a portion of which revolves around a portion of the inner binding thread to coil the 80 loop threads or strands around the inner binding thread, and means for causing a portion of the inner binding thread to revolve around and in the same direction as the said supporting and guiding means. 85

4. In a machine of the character described, the combination of a former, a revoluble carrier for an inner binding thread which carrier is coaxial with said former, a revoluble supporting and guiding member for the 90 loop strands of said rope or cord, and means for causing revolution of the said supporting and guiding member around said former and simultaneously around the said inner binding thread which extends through said 95 former.

5. In a machine for making ornamental rope or cord, the combination of means for guiding and supporting an inner binding thread, a revoluble carrier for said binding 100 thread coaxial with the said inner thread supporting and guiding means, a revoluble guiding member for the loop strands of the said cord one end of which is situated laterally of the said inner binding thread supporting and guiding means, and means for causing revolution of the said loop thread or strand guiding means around the said inner binding thread supporting and guiding 105 means. 110

6. In a machine for making ornamental rope or cord, the combination of means for guiding the inner binding thread of said rope or cord, a revoluble carrier for the said inner binding thread supported coaxially 115 with the said guiding means, a revoluble loop thread or strand guiding member having one end situated laterally of the said inner thread guiding means, means for causing revolution of the loop thread or strand guiding member around the said inner thread guiding means, and means for drawing off the inner binding thread and thereby causing the revolution of the said inner thread carrier in the same direction and at 120 a speed no less than the speed of revolution of the said loop thread or strand guiding member. 125

7. In a machine for making ornamental rope or cord, the combination of a station- 130

- ary inner binding thread supporting and guiding member, a carrier for supporting and supplying the said inner binding thread which carrier is revolved and is coaxial with the said inner binding thread supporting and guiding member, a guiding member for the loop threads or strands of the said rope or cord which member is pivotally supported at one end at a point coaxial with the said inner thread supporting and guiding member and the other end of which is situated at a point laterally of the said inner thread supporting and guiding member, means for causing revolution of the said laterally disposed end of the said loop thread guiding member around the said inner thread supporting and guiding member and simultaneously around a portion of the said inner binding thread, and means for drawing off the inner binding thread and thereby causing simultaneous revolution of the said inner binding thread carrier in the same direction and with substantially the same speed as the said loop thread or strand guiding member.

8. In a machine for making ornamental rope or cord, the combination of a revolute hollow member, a former supported upon the said hollow member, means for holding the said former stationary, the said former being coaxial with the said revolute hollow member, a revolute carrier for the inner binding thread of the said rope or cord which binding thread extends from the said carrier through an opening or perforation through the said former and which carrier is coaxial with the said revolute hollow member and with the said former, a loop thread or strand guiding member consisting of a tubular member pivoted adjacent to the outer end of the said carrier such pivot being on the extended axis of the said revolute hollow member and with the said former and the said tube extending from its pivoted point through the said hollow member at an angle to the axis thereof, the forward and inner end thereof terminating at a point laterally of and adjacent to the said former, and means for causing revolution of the inner forward end of the said ornamental thread or strand guiding member around the said former and the said inner binding thread which extends through the said former.

9. In a machine for making ornamental rope or cord, the combination of a stationary former, a spool for supplying the inner binding thread of the rope or cord, said spool being revolutely mounted and being coaxial with the said former, means for supporting loop strands or threads at a point laterally of and adjacent to the said former, means for causing revolution of the said threads or strands around the said former and the said inner binding thread, and means for drawing off the inner binding thread and thereby

causing revolution of the said spool simultaneously and in the same direction as the revolution of the supporting member for the said loop threads or strands.

10. In a machine for making ornamental ropes or cords, the combination of a stationary former, means for supporting an outer binding thread in juxtaposition with respect to the said former, a revolute carrier for supplying an inner binding thread which is carried into operative relation to the said former and to the said outer binding thread, a revolute member supporting and guiding ornamental threads or strands into position in proximity to said former and laterally thereof, means for causing revolution of the said supporting and guiding means around the said former and around the said inner binding thread, and means for drawing off the inner binding thread and thereby causing revolution of the said inner binding thread carrier in the same direction and with the same or somewhat greater speed than the speed of revolution of the said supporting and guiding member for the said threads or strands.

11. In a machine of the character described, the combination of a revolute member, a former carried by a support secured to said revolute member, the said support being provided with an opening through which an inner binding thread is guided, a revolute inner binding thread carrier which is coaxial with the said revolute member and with the said former, a guiding member for the ornamental loop threads or strands which member terminates at a point laterally of and in proximity to the said former and which guiding member is supported upon the said revolute member, whereby revolution of the latter causes revolution of the said guiding member around the said former and the support therefor, means for holding the said guiding member against revolution on its own axis, means interposed between the said guiding member and the support for the former for holding the said support and the said former against rotation or revolution, and means for drawing off the inner binding thread and thereby causing revolution of the said inner thread carrier in the same direction and with the same or slightly greater speed than that of the revolution of the said guiding member, whereby interference between the inner binding thread and the said guiding member or the threads or strands carried thereby is prevented.

12. In a machine for the making of ornamental rope or cord, the combination of a former, means for supporting inner and outer binding threads in operative relation to said former, a revolute tube for supporting and guiding ornamental threads or strands of different colors, the said tube being pro-

vided with means extending across the same for holding the threads or strands of different colors separate from each other, means for causing revolution of said tube around 5 said former and said inner binding threads, whereby the said ornamental threads or strands are coiled around said former and said inner binding thread.

13. In a machine for making ornamental 10 rope or cord, the combination of a former, means for supporting inner and outer binding threads in operative relation to said former, revolute means for supporting and guiding ornamental threads or strands of 15 different colors, the said means consisting of a tube having cross members located therein, which members separate the threads or strands in said tube, means for causing revolution of the tube around said former and 20 said inner binding thread whereby the said ornamental threads or strands are coiled around said former and said inner binding thread.

14. In a machine for making ornamental 25 rope or cord, the combination of a revolute member, a former supported thereon, means for holding said former stationary, means for supporting inner and outer binding threads in operative relation to said 30 former, means for coiling the ornamental threads or strands around said former and the inner binding thread, and a carrier for said inner binding thread which is coaxial with said former.

35 15. In a machine for making ornamental rope or cord, the combination of a stationary former, means for supporting inner and outer binding threads in operative relation to said former, means for receiving and 40 guiding a group of ornamental threads or strands which means revolves bodily around the said former to coil the said ornamental threads or strands around the said former and around the inner binding threads, and 45 means for controlling and regulating the movement of the said coiled threads or strands from the said former.

16. In a machine for making ornamental 50 rope or cord, the combination of a stationary former, means for supporting inner and outer binding threads in operative relation to said former, revolute tubular means for receiving and guiding ornamental threads or strands to a position laterally of the said 55 former, means for causing revolution of the said thread or strand guiding means around the said former, and around the inner binding thread to form the ornamental loops of the rope or cord, and means for controlling 60 and regulating the movement of the said loops from the said former.

17. In a machine for making ornamental 65 rope or cord, the combination of a revolute member, a former loosely supported thereon, means carried by said revolute

member for holding said former stationary, means for supporting inner and outer binding threads in operative relation to said former, means for coiling the ornamental threads or strands around said former and 70 inner binding thread, and a carrier for said inner binding thread.

18. In a machine for making ornamental 75 rope or cord, the combination of a revolute member having an axial opening extending therethrough through which a binding thread may pass, a former loosely mounted upon said revolute member, means for guiding and supporting ornamental threads or strands in operative relation to said former, 80 a portion of said means being supported upon said revolute member eccentrically thereof, such portion revolving around the said former, and means interposed between the said portion revolving around the said former and the latter to prevent rotation 85 of the said former.

19. In a machine for making ornamental 90 rope or cord, the combination of a revolute member, a member loosely supported upon said revolute member and axially thereof said member carrying a former, an ornamental thread or strand guiding means a part of which is supported upon said revolute member eccentrically of the said 95 loosely mounted member, said part revolving around the said loosely mounted member, the said loosely mounted member and the said part each being provided with a gear, and a gear supported upon the said revolute member and being in engagement with both of the said gears whereby as the said part and the gear carried thereby are revolved around the said loosely mounted member the latter is held against rotation.

100 20. In a machine for making rope or cord, the combination of means for supporting inner and outer binding threads in operative relation to each other, revolute means for supporting loop threads or strands in a 105 position laterally of said inner binding thread, means for causing revolution of said revolute means around said inner binding thread to coil or wind the said loop threads or strands around the same, a hollow revolute carrier on which the supply of said inner binding thread is wound, the axis of revolution of said carrier being in alignment with the axis of revolution of said 110 revolute means for supporting the loop threads or strands, the said loop threads or strands extending from their source of supply through said carrier, and means for drawing off the inner binding thread and thereby causing revolution of said carrier in the same direction as the revolution of the said loop thread or strand 115 supporting means and which means maintains the inner binding thread at its point of unwinding from the said carrier in 120

125 130

constant relation to said loop threads or strands.

21. In a machine for making ornamental rope or cord, the combination of a revoluble member, a guide for an inner binding thread carried by said member and being coaxial therewith, said guide having a former thereon, means for supporting an outer binding thread in operative relation to said former, 10 a carrier for a supply of the inner binding thread which carrier is coaxial with said revoluble member, means for drawing off the inner binding thread and thereby causing revolution of said carrier in the same direction and with the same speed as said revoluble member, the said carrier having an additional speed of revolution due to the unwinding of the said inner binding thread therefrom, a guide for the ornamental threads or strands which 15 extend from their source of supply through an opening through the said carrier and which guide is supported upon the said revoluble member and revolves therewith and a portion of said 20 guide being located laterally of and in proximity to said former whereby the ornamental threads or strands are wound or looped around said former, means for holding said 25 guide against rotation on its own axis, a gear 30 stationarily supported on said guide for the ornamental threads or strands, a gear stationarily supported on the guide for the inner binding thread, and a gear rotatably mounted on said revoluble member which 35 gear bodily revolves around said inner thread guide and which gear is in mesh with each of the other said gears for the purpose described.

22. In a machine for making ornamental 40 rope or cord, the combination of a former, means for supporting inner and outer binding threads in operative relation to said former, tubular revoluble means for receiving and guiding ornamental threads or 45 strands, means extending transversely of said tubular revoluble means for separating said threads into separate groups, means for causing revolution of the said means around said former and said inner binding thread, 50 whereby the said ornamental threads or strands are coiled around the said former and said inner binding thread.

23. In a machine for making ornamental 55 rope or cord, the combination of a revoluble member, a guide for an inner binding thread carried by said member and being coaxial therewith, said guide having a former thereon, means for supporting an outer binding thread in operative relation to said former, 6 a carrier having a supply of the inner binding thread which carrier is coaxial with said revoluble member and said former, means for drawing off the inner binding thread and thereby causing revolution of said car-

rier in the same direction and with the same speed as said revoluble member, the said carrier having an additional speed of revolution due to the unwinding of the said inner binding thread therefrom, a guide for the ornamental threads or strands which 70 extend from their source of supply through an opening through the said carrier and which guide is supported upon the said revoluble member and revolves therewith and a portion of said guide 75 being located laterally of and in proximity to said former whereby the ornamental threads or strands are wound or looped around said former, means for holding the guide for the ornamental threads or strands 80 against rotation on its axis, a gear stationarily supported on said last mentioned guide, a gear stationarily supported on the guide for the inner binding thread, and a gear rotatably mounted on said revoluble 85 member which gear also revolves around said inner thread guide and which gear is in mesh with each of the other of said gears for the purpose stated.

24. In a machine for making ornamental 90 rope or cord, the combination of means for guiding the inner binding thread of said rope or cord, a carrier for said inner binding thread supported co-axially with said guiding means and which carrier is provided 95 with an opening therethrough, a thread guiding member supported at one end at a point on the extended axis of the said carrier and extending through the opening in said carrier to a point laterally of the inner binding thread guiding means, means for causing revolution of a portion of the said 100 loop thread guiding member around the inner thread guiding means and around the said inner thread and means for drawing off the inner binding thread and thereby causing revolution of the said inner thread carrier in the same direction as the said loop thread guiding member.

25. In a machine of the character described, the combination of a rotary member, a former supported by said member, means for preventing rotation of said former, and means for winding threads around said former.

26. In a machine of the character described, the combination of a rotary member, a former supported thereby, a thread or strand guiding member supported in part by said rotary member and means interposed between the said former and the said thread guiding member to prevent rotation of the said former.

27. In a machine of the character described, the combination of a rotary member, a former supported thereby, a thread or strand guiding member having one end portion supported by said rotary member, and

gear mechanism interposed between the said former and the said thread guiding member to prevent rotation of the said former.

28. In a machine of the character described, the combination of a rotatable member, a former supported thereby, means actuated by the said rotatable member for coiling threads or strands around said former.

29. In a machine of the character described, the combination of a rotatable member, a former supported thereby, and a thread or strand guiding member extending through the said rotatable member and one end of which is located adjacent to the said former.

30. In a machine of the character described, the combination of a rotary member, a former supported thereby, and being concentric therewith, and a thread or strand guiding member which extends through the said rotary member, one end of the thread or strand guiding member being pivotally supported at a point on the axis of said rotatable member and the other end of the said thread or strand guiding member being eccentric with respect to said rotatable member.

31. In a machine of the character described, the combination of a rotatable member, a relatively stationary former and a thread or strand guiding means pivoted at one end upon a stationary support and having its opposite end portion supported upon the said rotatable member and having portions thereof located adjacent to the said former.

32. In a machine of the character described, the combination of a rotatable member, a former, and a thread or strand guiding member which extends longitudinally and diagonally through the said rotatable member, the said thread or strand guiding member terminating at a point adjacent to the said former.

33. In a machine of the character described, the combination of a rotatable member, a former supported thereby and being coaxial therewith, a support for an inner binding thread which support is coaxial with said rotatable member, a thread or strand guiding member pivotally supported at one end at a point on the extended axis of the said rotatable member, the said thread or strand guiding member extending through the said rotatable member to a point adjacent to and laterally of the said former, and a support adjacent to said former for an outer binding thread.

34. In a machine of the character described, the combination of a rotatable member, a member supported upon the said rotatable member and having a former secured to its outer end, and the said member having a gear secured thereto adjacent to the said rotatable member, a thread or strand guid-

ing member supported in part upon the said rotatable member, the said thread or strand guiding member having a gear secured thereto adjacent to the said rotatable member, means for holding the said thread or strand guiding member against rotation on its own axis, and a gear supported upon the said rotatable member and situated intermediate the said gears and being in mesh with both of them.

35. In a machine for making ornamental rope or cord, the combination of a stationary inner binding thread supporting and guiding member, a carrier for supporting and supplying the said inner binding thread, which carrier is revolute and is coaxial with the said inner binding thread supporting and guiding member, a guiding member for the loop threads or strands of the said rope or cord, which member is pivotally supported at one end at a point on the extended axis of the said inner thread supporting and guiding member, and the other end of which is situated at a point lateral of the said inner thread supporting and guiding member, and means for causing revolution of the said laterally disposed end of the said loop thread guiding member around the said inner thread supporting and guiding member and simultaneously around the said inner binding thread.

36. In a machine of the character described, the combination of a former, a support for said former, the said former and its support being relatively rotatable, and a thread or strand carrying and guiding means a portion of which revolves around said former whereby the thread is coiled around the same.

37. In a machine of the character described, the combination of a supporting member, a former supported by said member, means whereby said support and former are relatively rotatable, and a thread carrying and guiding means a portion of which revolves around the said former whereby the thread is coiled around the latter.

38. In a machine of the character described, the combination of a revolute support, a former supported by said support, a thread or strand guiding member partially supported upon said revolute support said thread or strand guiding member being angularly related to the axis of said revolute support and being revolved by the rotation of said support around such axis and around said former, and means intermediate said thread or strand guiding means and a part having connection with said former for holding the latter against rotation.

39. In a machine of the character described, the combination of a revolute support, a former having connection with said

support and being supported thereby, and a thread or strand guiding device partially supported upon said support and by the revolution of the latter being revolved around 5 said former.

40. In a machine of the character described, the combination of a rotatable member and a device extending into one end of said rotatable member, the said device being 10 stationary, and the said rotatable member being provided at the end into which said device extends with eccentrically situated thread guiding means which revolves around said device to wind a thread or threads 15 around the same.

41. In a machine of the character described, the combination of a rotatable member, a device extending into one end of and being supported by said rotatable member, 20 means for preventing rotation of said device, the said rotatable member being provided in the end portion into which said device extends with eccentrically situated thread guiding means which revolves around said 25 device to wind a thread or threads around the same.

42. In a machine of the character described, the combination of a member hav-

ing thread supporting and guiding means situated eccentrically of one end portion 30 thereof, a device situated in axial alinement with the said member, means for effecting relative rotation of the said member and said device whereby a thread or threads supported in said thread supporting and guiding 35 means is wound around the said device.

43. In a machine of the character described, the combination of a rotatable member, a device situated axially of and extending into one end of said rotatable member, 40 means for preventing rotation of said device, the said member being provided at the end portion into which said device extends with eccentrically situated thread guiding and supporting means which revolves around 45 said device to wind a thread or threads around the same, and means for causing the said threads to slide forwardly on said device.

In testimony that I claim the foregoing 50 as my invention, I have hereunto signed my name this 28th day of June, A. D. 1911.

FRANKLIN W. OEHRLIE.

In the presence of—

CYRUS N. ANDERSON,
GEO. H. WEIDNER.
